[57] CLAIM

The ornamental design for a combination cordless handset telephone and stand, as shown and described.

DESCRIPTION

FIG. 1 is a front elevational view of a combination cordless handset telephone and stand, showing my new design in cradled relationship;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and

FIG. 7 is a bracket associated front perspective view of the stand alone with antenna extended, and a front perspective view of the telephone handset shown separated from the stand and in opened position with antenna extended.

FIG. 1

FIG. 2

FIG. 3

FIG. 4

FIG. 5

FIG. 6

FIG. 7
